DANCING FIGURE TOY

Raymond Lohr, Erie, Pa., assignor to Louis Marx & Company, Inc., New York, N. Y., a corporation of New York

Application April 28, 1936, Serial No. 76,746

20 Claims.

(Cl. 46—138)

This invention relates to toys, and more particularly to dancing figure toys.

The primary object of the invention is to generally improve dancing figure toys. A more particular object resides in the provision of such a toy in which the figure will be caused to move not only vertically to simulate dancing, but also from side to side. In accordance with a further feature and object of my invention, the vibration 10 and movements of the toy are given an irregularity such as to simulate tap dancing.

Other objects of my invention concern the general organization and arrangement of the toy, and are to simulate a small stage with an appropriate back drop; to conceal the motor-works and operating mechanism behind the drop; and to support and control the movement of the figure toy by means of a support arm which extends in a relatively inconspicuous manner 20 from the toy rearwardly through an opening in the back drop.

To the accomplishment of the foregoing and other more particularized objects which will hereinafter appear, my invention consists in the toy tap dancer elements, and their relation one to the other, as hereinafter are more particularly described in the specification and sought to be defined in the claims. The specification is accompanied by a drawing in which:

30 Fig. 1 is a perspective view of one form of toy embodying features of my invention;

Fig. 2 is a section taken in elevation through the operating mechanism of the toy; and

35 Fig. 3 is a rear elevation looking in the plane of section line 3—3 of Fig. 2.

Referring to the drawing and more particularly to Fig. 1, the toy comprises a figure 12 disposed above the forward part of a suitable base 14 and in front of an upright plate 16 mounted on said base. If desired, the base 14 and plate 16 may be suitably shaped and decorated to simulate a stage and back drop such as is used in theatres, restaurants, night-clubs, and the like. The figure 12 is mounted on the forward end of a support arm 18 which extends rearwardly from the figure through an opening 20 in the plate or drop 16. Appropriate motor-works, generally designated 22 in Fig. 2, are disposed in back of and concealed by the plate 16. The figure 12 is caused to dance by movements given to support arm 18 by the motor 22.

Considering the arrangement in greater detail, the figure 12 is preferably a loosely jointed figure, 55 that is, the arms 24 are hung loosely from the

body at the shoulders by pivotal connections 26. The legs 28 are suspended freely from within the body, and the legs are themselves loosely articulated at the knees 30. The relative disposition of the parts and the range of vertical movement of the support arm 18 are such that the feet 32 of the figure are lifted clear of base 14 when the figure is elevated, but rest on the base when the figure is lowered.

Referring now to Figs. 2 and 3, the inner or rear end of support arm 18 is pivotally mounted at 34 in a suitable vertical frame plate 36 forming the forward wall of the spring motor frame. A cam wheel 38 is located beneath arm 18 and is provided with teeth or cam projections 40 which bear directly against arm 18. As will be noted in the drawing, the cam 38 is preferably made large in diameter and is provided with a large number of camming teeth. These teeth are preferably irregularly spaced and irregularly dimensioned. The arm 18 is vibrated or oscillated in a vertical plane by cam wheel 38, and the dimensions and groupings of the teeth 40 are such as to impart a desired rhythm and variety to the dancing movement of the figure.

An important feature of the present toy resides in the fact that the figure is moved from side to side, as well as up and down. For this purpose, I provide a suitable sidewardly movable plate or member 42 having a vertical slot 44 through which the support arm 18 passes. Slot 44 is disposed immediately in back of the opening 20 previously referred to, and the said opening is preferably dimensioned to accommodate an appreciable side to side movement of slot 44 and with it the support arm 18. The spring motor-works is arranged to move the plate or member 42 from side to side, thus giving the support arm 18 a rather complex oscillatory movement having vertical and horizontal components.

The sideward movements of the figure are preferably made relatively slow and infrequent compared to the vertical movements, and this result is brought about in a comparatively simple manner by using the cam wheel 38 as a crank or actuating member for causing sideward displacement of member 42. More specifically, member 42 is pivotally mounted at its upper end 46 on the plate or drop 16. Cam 38 carries an eccentrically located pin 48 which projects forwardly from the cam wheel and is thus adapted to bear against the depending lower portion 50 of member 42. For a simple uniform side to side movement of member 42, the member may be provided with a slot into which crank pin 48 passes. How-

ever, I prefer to make even the side to side movement less obviously regular. The plate or member 42 is therefore cut away to form the generally hook-shaped outline indicated in dotted lines 5 at 50 in Fig. 3. The cam wheel 38 rotates in a clockwise direction, as viewed in Fig. 3. As pin 48 moves from its bottom position upwardly, it bears against the portion 50 of member 42, thus carrying the member toward the left, as viewed 10 in Fig. 3, or to the broken-line position of the dancer shown in Fig. 1. When pin 48 passes above the upper end of portion 50, the member 42 is freed for return movement toward the right. Inasmuch as the upper peripheral portion of 15 cam wheel 38 bearing against support arm 18, is moving toward the right, the support arm is carried quickly toward the right, the member 42 being moved with the support arm. The dancer is then moved to the solid-line position shown in 20 Fig. 1. The parts then dwell in the position shown in Fig. 3, the figure 12 executing a number of steps in that position before it is again carried toward the opposite side by the cooperation of crank pin 48 and the lower portion 50 of the 25 slotted plate 42.

As so far described, the toy dancing figure might be rigidly secured at the forward end of the operating or support arm 18. However, one important advantage of the present construction is 30 the ease with which the figure may be arranged for an oscillation or sideward swinging movement about the support arm. As here illustrated, arm 18 is formed of round wire or rod, and it passes freely through the figure at a point above the 35 center of gravity of the figure. The figure then remains normally in generally upright position, but when the figure is swung to one side by arm 18, the lower or heavier part of the figure continues its movement and swings outwardly beyond the support rod. Similarly, when the support arm moves in opposite direction, the feet tend to lag behind, thus bringing the figure to angular position, and, finally, at the end of the sideward movement, the feet continue their 45 movement, thus swinging the figure in opposite direction. The result of this additional movement of the figure, combined with the movements previously described, is that the figure simulates the spirited or flying movement of a modern stage 50 dance and not the mere shuffling in fixed bodily position of the ordinary toy jigger.

The motor comprises a main spring 52 the outer end of which is secured to the motor frame at 54, and the inner end of which is connected to 55 a suitable winding stem 56 a part of which is bent to form a winding key 58. Stem 56 is connected to a main gear 60 by means of conventional ratchet mechanism, so that the main spring may be wound without driving the entire toy. 60 Gear 60 has fixedly secured thereto a suitable collar 62 carrying at its forward end a plate 64 which is secured to and forms a part of cam wheel 38. Cam wheel 38 is thus caused to rotate with gear 60 and winding stem 56 when the motor 65 is unwinding. Plate 64 serves an additional function in providing a rigid support for crank pin 48 because the crank pin passes through both the cam wheel 38 and the plate 64.

The motor is further provided with a train 70 of step-up gearing which, however, is used primarily for speed governing and control purposes. Specifically, gear 60 meshes with a pinion 66 fixed to a gear 68 which in turn meshes with a pinion 70 fixed to a gear 72 which in turn meshes 75 with a pinion 74 fixed to a gear 76 which in turn

meshes with a terminal pinion 78. It will be understood that pinions 66 and 74 are loosely carried by spindle 80, while pinions 70 and 78 are loosely carried by spindle 82. Pinion 78 carries an eccentrically shaped plate or weight 84. Because of the high speed at which this unbalanced member is rotated, it provides a governing influence on the speed of unwinding of the spring motor.

At the same time, governor member 84 may 10 be used as a stop element to control the starting and stopping of the spring motor. For this purpose, I provide a stop lever 86 pivoted on the motor frame at 88 and having a bent inner end 90 adapted to be moved into the path of the enlarged or eccentric part of member 84. In other words, by moving the opposite or manually movable end 92 of the stop lever downwardly, the end 90 is elevated, thus freeing the spring motor for operation. When, on the other hand, the manually movable end 92 is elevated, the motor is locked against unwinding.

When, as is here the case, the support arm 18 is bent upwardly rather than straight, it is necessary to prevent the arm from turning about its longitudinal axis, for otherwise the figure would be unduly lowered. Referring to Fig. 2, I provide an auxiliary arm 94 having one end fixedly secured to arm 18 at 96, and having its other end received in a vertical slot 98 cut in the motor 30 frame plate 36. It will be manifest that the auxiliary arm 94 in no way interferes with the desired universal movement of support arm 18 about its pivotal connection 34, for the arm may be moved both sidewardly and vertically with the 35 utmost freedom. However, the arm is prevented from rotating or oscillating about its longitudinal axis, because of the cooperating relation of auxiliary arm 94 and slot 98.

The frame-work of the motor comprises two 40 main pieces of metal. The first piece, numbered 36, extends generally parallel to plate 16 but is turned forwardly at the upper and lower corners to form spacer arms 100 which are connected to plate 16 by appropriate tongue and slot connections. The second piece, numbered 102, acts as 45 a back plate for the frame and is turned forwardly at its side edges to form side walls 104 which are joined to the forward wall 36 by appropriate tongue and slot connections.

It is believed that the construction and operation, as well as the many advantages of my improved dancing figure toy, will be apparent from the foregoing detailed description thereof. The figure is not marred by a visible vertical support rod extending upwardly from the base. The absence of such a support rod also contributes to 55 permit a perfectly free active movement of the legs of the figure, particularly when the figure is moved from side to side as well as vertically. 60 This side to side movement adds greatly to the realism of operation. Considerable range of movement is obtained without equal movement of the visible portion of the support arm, for the reason that the support arm is moved with an oscillatory movement about a fixed pivot. This pivot is located relatively near the back plate or drop, and the opening through the back plate may therefore be made relatively small in dimension, for the range of movement at the back plate is only a small fraction of the final movement at the figure. The vertical movements may be so timed and spaced with respect to one another and with respect to the sideward move- 70 75 75

ments of the figure, as to produce a realistic effect.

It will be apparent that while I have shown and described my invention in a preferred form, 5 many changes and modifications may be made in the structure disclosed, without departing from the spirit of the invention, defined in the following claims.

I claim:

10 1. A dancing toy comprising a loosely jointed figure, a stage or platform on which the figure simulatedly dances, means causing at least part of the figure to move up and down and additional means to move the entire figure bodily 15 from one side to the other side of the aforesaid stage or platform, and motor mechanism for causing both of the aforesaid movements.

2. A dancing toy comprising a loosely jointed figure, a single support arm extending rearwardly 20 from said figure, the forward end of the arm passing loosely into the figure at a point above the center of gravity thereof and forming a horizontal pivot about which the figure may swing freely 25 from side to side, means causing at least part of the figure to vibrate up and down to simulate dancing, and means to move the aforesaid support arm from side to side.

3. A dancing toy comprising a loosely jointed figure, a single support arm extending rearwardly 30 from said figure, the forward end of the arm passing loosely into the figure at a point above the center of gravity thereof and forming a horizontal pivot about which the figure may swing freely 35 from side to side, means causing at least part of the figure to move up and down to simulate dancing, means to move the aforesaid support arm from side to side, and a single motor for causing both of the aforesaid movements.

4. A dancing toy comprising a loosely jointed 40 figure, motor-works disposed behind and spaced from said figure, a single support arm extending from said figure rearwardly to said motor-works, the forward end of the arm passing loosely into the figure at a point above the center of gravity 45 thereof and forming a horizontal pivot about which the figure may swing freely from side to side, and means in said motor-works for moving the support arm from side to side.

5. A dancing toy comprising a loosely jointed 50 figure, motor-works disposed behind and spaced from said figure, a single support arm extending from said figure rearwardly to said motor-works, the forward end of the arm passing loosely into the figure at a point above the center of gravity 55 thereof and forming a horizontal pivot about which the figure may swing freely from side to side, means in said motor-works for vibrating the support arm up and down, and additional means for moving the aforesaid support arm from side to side.

6. A dancing toy comprising a loosely jointed 60 figure, motor-works disposed in back of and spaced from said figure, a support arm extending from said figure rearwardly to said motor-works, and means in said motor-works for moving the support arm with a complex motion having components in a plurality of different directions.

7. A dancing toy comprising a loosely jointed 70 figure, motor-works disposed behind and spaced from said figure, a support arm extending from said figure rearwardly to said motor-works, means in said motor-works for vibrating the support arm up and down, and additional means

in said motor-works for oscillating the support arm from side to side.

8. A dancing toy comprising a loosely jointed figure, motor-works spaced from said figure, a support arm extending from said figure to said motor-works, the end of said support arm remote from said figure being pivotally mounted for universal movement, and means in said motor-works for oscillating the support arm with a complex motion having components in a plurality of different directions. 10

9. A dancing toy comprising a loosely jointed figure, motor-works located in back of and spaced from said figure, a single support arm extending rearwardly from said figure to said motor-works, the forward end of the arm passing loosely into the figure at a point above the center of gravity thereof and forming a horizontal pivot about which the figure may swing freely from side to side, a toothed cam wheel rotated by said motor-works, said wheel having a plurality of teeth disposed on its periphery, a part of said support arm resting on the periphery of said cam wheel and being vibrated up and down by said cam wheel, and additional means 25 for moving the aforesaid support arm from side to side.

10. A dancing toy comprising a loosely jointed figure, motor-works spaced from said figure, a single support arm extending from said figure to said motor-works, a toothed cam wheel of relatively large diameter rotated by said motor-works, said wheel having a plurality of teeth disposed on its periphery for vibrating the support arm up and down, said teeth being irregular in spacing and dimension in order to produce a desired variety in the dancing movement of the figure, and additional means for horizontally reciprocating the aforesaid support arm. 30

11. A dancing toy comprising a loosely jointed figure, motor-works located in back of and spaced from said figure, a single support arm extending rearwardly from said figure to said motor-works, a toothed cam wheel of relatively large diameter rotated by said motor-works, said wheel having a plurality of teeth disposed on its periphery, said teeth being irregular in spacing and dimension in order to produce a desired variety in the dancing movement of the figure, a part of said support arm resting on the periphery of said cam wheel and being vibrated up and down by said cam wheel, and additional means for moving the aforesaid support arm from side to side. 45

12. A dancing toy comprising a loosely jointed figure, motor-works located in back of and spaced from said figure, a support arm extending rearwardly from said figure to said motor-works, a movable plate having a vertically disposed slot through which the support arm passes, means driven by said motor to move the plate and with it the support arm from side to side, and means driven by said motor to vibrate the support arm up and down. 55

13. A dancing toy comprising a loosely jointed figure, motor-works located in back of and spaced from said figure, a support arm extending rearwardly from said figure to said motor-works, a toothed cam wheel rotated by said motor-works, said wheel having a plurality of teeth disposed on its periphery, a part of said support arm resting on the periphery of said cam wheel and being vibrated up and down by said cam wheel, a movable plate having a vertically disposed slot through which the support arm passes, 60

70

75

- and means driven by said motor for moving the plate from side to side.
14. A dancing toy comprising a loosely jointed figure, motor-works located in back of and spaced from said figure, a support arm extending rearwardly from said figure to said motor-works, a toothed cam wheel rotated by said motor-works, said wheel having a plurality of teeth disposed on its periphery, a part of said support arm resting on the periphery of said cam wheel and being vibrated up and down by said cam wheel, a movable plate having a vertically disposed slot through which the support arm passes, and means on said cam wheel cooperating with said plate to move the plate from side to side during rotation of the cam wheel, whereby the support arm is rapidly vibrated in a vertical direction and is more slowly moved in a sideward direction.
15. A dancing toy comprising a loosely jointed figure, motor-works located in back of and spaced from said figure, a support arm extending rearwardly from said figure to said motor-works, a toothed cam wheel of relatively large diameter rotated by said motor-works, said wheel having a plurality of teeth disposed on its periphery, said teeth being irregular in spacing and dimension in order to produce a desired variety in the dancing movement of the figure, a part of said support arm resting on the periphery of said cam wheel and being vibrated up and down by said cam wheel, a movable plate having a vertically disposed slot through which the support arm passes, and means on said cam wheel cooperating with said plate to move the plate from side to side during rotation of the cam wheel, whereby the support arm is rapidly vibrated in a vertical direction and is more slowly moved in a sideward direction.
16. A dancing toy comprising a base simulating a stage, an upright plate near the back of the stage simulating a stage drop, a loosely jointed figure disposed above the forward part of the stage, a support arm extending rearwardly from said figure through an opening in said drop, the forward end of the arm passing loosely into the figure at a point above the center of gravity thereof and forming a horizontal pivot about which the figure may swing freely from side to side, spring motor-works mounted in back of said drop, and means driven thereby for moving the support arm from one side to the other side of the aforesaid stage.
17. A dancing toy comprising a base simulating

ing a stage, an upright plate near the back of the stage simulating a stage drop, a loosely jointed figure disposed above the forward part of the stage, a support arm extending rearwardly from said figure through an opening in said drop, spring motor-works mounted in back of said drop, and means driven thereby for vibrating the support arm up and down and from side to side.

18. A dancing toy comprising a base simulating a stage, an upright plate near the back of the stage simulating a stage drop, a loosely jointed figure disposed above the forward part of the stage, a support arm extending rearwardly from said figure through an opening in said drop, spring motor-works mounted in back of said drop, a plate movably mounted in back of said drop, said plate having a vertical slot disposed in back of the aforesaid opening through which the support arm passes, a toothed rotatable cam wheel bearing against the aforesaid support arm, said support arm being pivotally mounted for universal movement, said plate and cam wheel being driven by said spring motor to oscillate the support arm in different directions.

19. A dancing toy comprising a base simulating a stage, an upright plate near the back of the stage simulating a stage drop, a loosely jointed figure disposed above the forward part of the stage, a support arm extending rearwardly from said figure through an opening in said drop, spring motorworks mounted in back of said drop, a member pivoted at one end to said drop, said member having a vertical slot disposed in back of the aforesaid opening through which the support arm passes, a toothed cam wheel of large diameter rotatably mounted adjacent said member and bearing against the aforesaid support arm, the rear end of said support arm being pivotally mounted for universal movement, said member and cam wheel having means which cooperate for slowly moving the member in a direction opposite the direction of movement of that part of the cam wheel bearing against the arm, but which means disengage to permit more rapid return movement of the support arm by the cam wheel.

20. A dancing toy comprising a loosely jointed figure, a support arm extending from said figure rearwardly, said figure being freely pivoted on said support arm, and motor-works for vibrating the support arm up and down and for moving the support arm from side to side.

RAYMOND LOHR.
